TIME FUSE

Georges Perrenoud, Le Locle, Switzerland

Application December 27, 1937, Serial No. 181,923
In Switzerland January 30, 1937

2 Claims. (Cl. 102—36)

This invention relates to a new and improved regulating mechanism for the clockwork of mechanical time fuses designed for artillery projectiles.

5 Heretofore upon the firing of a projectile the pendulum controlling the clockwork exerted a relatively great tractive force upon the regulating spring for the clockwork and the other rather small associated elements which was liable to cause a breakage of the regulating spring. Such 10 action would also produce a fatigue in the spring destroying the elastic properties thereof. Furthermore due to such force the sleeves suspending the spring might slide with relation thereto and thus modify the active or effective length of 15 the spring. Also such force was liable to cause a sliding of the pendulum shaft in the connection provided between the pendulum and the regulating spring and thereby modify the oscillating period 20 of the pendulum. It is an object of the invention to correct the above defects.

It is a further object of the invention to associate a shock absorbing means with the regulating spring so as to protect such spring particularly 25 at the moment of firing when the acceleration is the greatest.

A further object of the invention is to provide means to counteract the effect of the shock upon the torsion spring extending along the axis of 30 the projectile upon the firing of the projectile and also to protect such spring from the strain imposed thereon due to the weight of the pendulum itself.

A further object of the invention is to provide 35 a resilient support for both the torsion spring and the pendulum support thereby.

A further object is to provide means whereby all strain is removed from the regulating spring.

With these and other objects in view which will 40 become apparent as the description proceeds the invention consists in the combination of elements hereinafter described in detail, claimed in the claims and shown in the drawing in which—

Fig. 1 is a cross sectional view of the head of a 45 projectile with the body thereof shown only partially.

Fig. 2 is a plan view of a detail.

Referring to the drawing in which similar reference characters are used to indicate like elements 50 the pendulum is shown at 1 and the regulating spring formed as a torsion spring and consisting of a steel wire, for example, is shown at 2. The clockwork for the fuse has been omitted from the drawing since the invention has reference 55 only to the regulating mechanism therefor.

The pendulum 1 and the regulating spring 2 extend along the axis of the projectile whose conical shell head is shown at 3. The lower pivot of the pendulum is mounted in the body 4 of the projectile on which the head 3 is screw threaded. 5 The upper pivot for the pendulum is seated in a collar member 5 which is freely mounted in the cylindrical recess 6 provided in the socket member 7. The socket member 7 comprises a plate 8 which extends over the recess 9 within which the pendulum 1 is located. The plate 8 is connected to the body 4 of the projectile by means of the screws 11 of which only one is shown on the drawing. The shaft of the pendulum extends through a bore 12 provided in the plate 8 and an upper bearing 13 and a lower bearing 14 is provided for such a shaft. These bearings 13 and 14 and the opening below the lower end of the bearing 14 which will permit adjustment of the lower pivot of the pendulum shaft allow the pendulum and the sleeve 20 5 a certain amount of movement or axial play which is limited by the lower surface of the recess 9 and the lower surface of the plate 8.

The torsion or regulating spring 2 is connected at its lower end to the sleeve member 5 25 and at its upper end to the cylindrical sleeve member 5'. The sleeve member 5' is located in an opening, which is preferably circular, of the member 15 which may have any desired shape. The member 15 is mounted upon the upper end of 30 the protecting tube 16 which is secured in any desired way to the socket member 7. At about the central portion of the protecting tube 16 for the torsion spring 2 there is provided a washer member 17 having a central aperture which assists 35 in guiding the spring.

As is obvious from the construction above described the sleeve members 5 and 5' are capable of movement along the longitudinal axis of the projectile. The sleeve member 5 may have such 40 movement in the recess 6 provided in the socket member 7 while the sleeve member 5' is capable of such movement in the opening provided in the member 15.

The support for the sleeve member 5 consists of a shock absorbing spring 18 which is secured to the member 15 by rivets or any other desired securing means. The spring 18 may be star shaped, for example, and is secured at its central 50 portion to the sleeve member 5'. As is obvious any other desired type of resilient mounting for the sleeve member 5' may be utilized in order to permit the sleeve member 5' to have limited axial movement relative to its support extending be- 55

tween the bearing 20 and a bar 21 mounted on the member 15.

The spring 18 normally holds the sleeve member 5' in its upper position as shown in the drawing in which the sleeve member 5' bears against the lower surface of the bar 21. It naturally follows that the regulating spring 2 and the pendulum 1 associated therewith are normally suspended from the sleeve member 5' which is held in its uppermost position by the action of the shock absorbing spring 18. However upon firing the projectile and the subsequent great acceleration given to the projectile body, the pendulum due to its inertia will withdraw the sleeve member 5' from the bar member 21 against the action of the spring 18 thereby materially reducing the force of the shock upon the torsion spring itself.

As a further safeguard the axial play of the sleeve member 5' is preferably greater than that of the pendulum 1 so that upon firing the torsion spring may be completely relieved from the consequent shock during the initial axial acceleration of the projectile.

As the acceleration ceases the various members of the regulating mechanism will gradually resume their original or normal position through the action of the spring 18 and the pendulum will then begin to oscillate.

As will be noted from the construction described when the pendulum is in operation the sleeve member 5 and the bearings 13 and 14 of the pendulum shaft are not in contact with any other frictional surface since the entire regulating system is suspended from the sleeve member 5'. From this construction it follows that the elements of the regulating system will function under the best possible conditions and with the elimination of practically all friction.

The above described embodiment is a preferred construction which is given by way of

example only since it is obvious that the invention may be modified within rather wide limits without departing from the gist of the invention. Although in practice the shock absorbing means are formed by one or more springs of various types these means may also include or comprise any resilient or elastic element which is suitable for and capable of accomplishing the functions of a shock absorber. For example such shock absorbing effect may be obtained by mounting the protective tube 16 resiliently in an axial direction.

I claim:

1. A regulating mechanism for the clockwork of a mechanical time fuse for projectiles comprising a pendulum, a torsion regulating spring located along the longitudinal axis of the projectile supporting said pendulum, a protecting tube encircling said spring, a support for said spring at its forward end, a shock reducing spring supporting said support located upon the forward end of said protecting tube, a coupling member connecting the rear end of said regulating spring to the axis of said pendulum, and said pendulum being disposed in the body of said projectile with relatively slight axial play.

2. A regulating mechanism for the clockwork of a mechanical time fuse for projectiles comprising a pendulum, a torsion regulating spring located along the longitudinal axis of the projectile supporting said pendulum, a protecting tube encircling said spring, a support for said spring at its forward end, a star shaped shock reducing spring supporting said support located upon the forward end of said protecting tube, a coupling member connecting the rear end of said regulating spring to the axis of said pendulum and said pendulum being disposed in the body of said projectile with relatively slight axial play.

GEORGES. PERRENOUD.
